BATES VALVE BAG COMPANY, OF CHICAGO, ILLINOIS, A CORPORATION OF WEST
VIRGINIA.

DEVICE FOR WIRE-TYING BAGS.

1,242,353.

Specification of Letters Patent.

Patented Oct. 9, 1917.

Application filed May 22, 1915. Serial No. 29,773.

To all whom it may concern:

Be it known that we, AUGUST S. KUHN and REGINALD R. MILLER, citizens of the United States, residing at Chicago, in the county of Cook and State of Illinois, have invented certain new and useful Improvements in Devices for Wire-Tying Bags, of which the following is a specification.

Our invention relates to a device for wire-tying bags and has for its object to provide means whereby ties may be easily twisted upon the bag and the wire-tying device easily and automatically released from the tie.

It is illustrated in the accompanying drawings wherein—

Figure 1 is a side elevation of the device with the bag and tie in position;

Fig. 2 is a similar view of the same with the tie completed;

Fig. 3 is a similar view after the twisted tie has been released;

Fig. 4 is a longitudinal detail section;

Fig. 5 an end view of the hook.

Fig. 6 is a side elevation of the device with a variation in the twist on the rod shown by breaking away part of the handle.

Like parts are indicated by the same letters in all the figures.

A is a rod having at its outer end the boss B from which projects the small rod B¹ on which is mounted the hook piece B² having the two hooks B³, B⁴ integral with it and faced in the same rotary direction and forming a substantially S-shaped piece. The rod A has spiral grooves C, C and at its inner end is reduced at C¹ provided with the loose collar C² held in position by the screw C³ and acting as a support for the link C⁴ pivotally attached to the collar at C².

D is a handle apertured to permit the passage of the rod A and provided with the lateral projections D¹, D² each with a transverse hole in which is mounted the screw bolt D² provided at its inner end with the ball D³. Each of these balls rides in one of the grooves.

E is a cap about the rod and secured to the handle by the screws E¹. It contains

the spiral spring E² which at one end bears against the end of the handle and at the other against the end E³ of the sleeve E⁴ which surrounds the rod. F, F are the two sides of a wire loop. F¹, F² are the upper ends of said loop and F² is the folded bag within the loop.

In Fig. 6 we have shown the same pitch of the screw at the left end of the rod as in the other figures and at the right a long slow thread or pitch. The object of this arrangement, of course, is to cause a rotational movement of the hook relatively slow with reference to the movement of the handle at the beginning of the twist. The slow pitch of the spiral at the beginning gives more power with reference to the amount of twist effected and it is at that point that such power is required. As the pitch increases, the twist being well started, less power is required. This slow pitch is indicated by the letter G.

We do not wish to be limited to the particular form, size, proportion and arrangement of these several parts, as obviously great changes could be made without departing from the spirit of our invention. We wish our drawings to be taken in a sense as diagrammatic, although they do represent an operative device.

The hooks B³, B⁴ in the preferred form are formed of a single integral thin plate 80 perpendicular to the shank B¹ and so arranged that the slot between them and the member B² will be comparatively deep and narrow. This is an advantage but not absolutely essential and the piece would function 85 properly if the slots were not so deep; but with the device arranged as shown, the slots being curved about the center of rotation, the operation is better than if the arrangement were slightly different.

The use and operation of our invention are as follows:

Assuming that the parts are in the position shown in Fig. 1, the link C⁴ being against the breast of the operator, the tie 95 loop having had its two ends caught in the

- two hooks while its body portion is gathered around the top of a puckered bag, to complete the tie it is only necessary to bring the handle to the limit of its motion toward the 5 operator or toward the left. This will cause the rod A to rotate and that rotation will rotate the hook in the direction indicated by the arrow in Fig. 5, thus tending to keep the upset ends of the tie loop in hooked relation. 10 The tie will now be twisted as indicated in Fig. 2 so as to complete the tie and tighten it about the bag.
- The sleeve or buffer member E⁴, with its end E³, is operatively connected to the tie 15 holder, and with the spring E² and buffer E³ always normally in contact; while the spring is compressed by the pushing in of the buffer member by striking against the ring or collar C² only at or near the end of the 20 tie-twisting movement. At this time, when the operator releases his hold on the handle D, the compressed spring presses against the handle D and thereby causes the reverse turn on the shaft which releases the wire tie 25 from the tying hooks, and the parts E⁴ and D are again pressed apart from the position shown in Fig. 2 to that indicated in Figs. 3 and 4.

In thus moving the handle to the limit of 30 its motion toward the left as indicated in Fig. 2, the spring E² will be compressed and if then the handle be free this spring will force the handle toward the right, thus rotating the hook piece slightly in the reverse 35 direction and disengaging the hooks from the ends of the wire tie. This is very important in the use of such machines or tools. They are generally used by more or less inexperienced help and any effort required to 40 manipulate or operate the tool beyond what is absolutely essential should be avoided. The automatic release due to this retracting spring is very effective in releasing and discharging the tie and therefore the bag and 45 greatly facilitates the operation, for the operator immediately upon completing the tie releases the handle and proceeds to manipulate another tie without having to stop to disengage the tool. The importance of this 50 will be evident when it is remembered that tens of millions of such bags are wire-tied every year.

Attention is called to the fact that the spring buffer arrangement is so arranged 55 that when the twisting movement has been completed the spring then comes into operation to return the parts and rotate them through a short distance so as to disengage the tie-holder from the tie. Attention is 60 also called to the simplicity of the device wherein the axes of the slots are parallel with the axis of rotation of the twisting tool and so parallel with the wire ends as they are twisted. The slots are deep and nar-

row and are substantially concentric. Since 65 these slots are curved and curved about the center of rotation of the twisting tool, it is obvious that they take hold of the wire, and the rotation of the tool tends to lock the wires into the slots, and because they are 70 curved it is easy for them to be disengaged by the relatively light pressure of the releasing spring.

It will be observed that the spring buffer is so arranged that it rotates the shank in 75 the opposite or untwisting direction substantially through one whole revolution so as to disengage the hook from the ends of the ties. Clearly, if the resistance is very great, the spring may not rotate the hook 80 through a whole revolution, but under no conceivable circumstances will there be such a resistance as will make it impossible for the hook to be rotated back far enough to disengage it from the ends of the tie, though 85 normally a reverse rotation of one revolution will take place.

We claim:

1. A wire-tie twisting tool comprising a tie holder having parts adapted to hold the 90 ends of the tie, faced in the same rotational direction, means for rotating the holder in one direction to twist the tie, and means for automatically rotating it sufficiently in the opposite direction at the end of the twisting 95 action to release the tie, said means operative to rotate the parts in the opposite direction only at the end of the twisting movement.

2. A wire-tie twisting tool comprising a 100 tie holder having parts adapted to hold the ends of the tie and faced in the same rotational direction, means for rotating the holder in one direction to twist the tie, and means for automatically rotating it approximately 105 one revolution only in the opposite direction at the end of the twisting action to release the tie, said means comprising a spring, a buffer member operatively connected to the tie holder, the spring and 110 buffer member being so positioned that they come in contact with one another and the spring is compressed only at the end of the twisting movement.

3. A wire-tie twisting tool comprising a 115 tie holder having projecting slotted parts, the slots being deep and narrow and open on opposed sides of the slotted part in the same rotational direction, said slots being parallel with the axis of rotation of the 120 twisting tool.

4. In a wire-tie twisting tool comprising a shank and means for rotating it, a pair of curved fingers forming an S-shaped hook with narrow deep slots curved about the 125 center of rotation of the shank and opening in the same rotational direction.

5. In a wire-tie twisting tool comprising

a shank and means for rotating it, a pair of curved fingers forming an S-shaped hook with narrow deep slots curved about the center of rotation of the shank and opening 5 in the same rotational direction, said hooks being formed of a single integral thin plate perpendicular to the shank.

Signed at Chicago, Illinois, this 19th day of May, 1915.
